DESIGN FOR A FLOOR POLISHING MACHINE OR SIMILAR ARTICLE

Orville W. Thraillkill, Wellington, Kans.

Application May 6, 1941, Serial No. 100,806

Term of patent 7 years

To all whom it may concern:

Be it known that I, Orville W. Thraillkill, a citizen of the United States, residing at Wellington, in the county of Sumner and State of Kansas, have invented a new, original, and ornamental Design for a Floor Polishing Machine or Similar Article, of which the following is a specification, reference being had to the accompanying drawing, forming part thereof.

Figure 1 is a view in side elevation of a floor polishing machine or similar article, embodying my new design;

I claim:

The ornamental design for a floor polishing machine or similar article, substantially as shown.

ORVILLE W. THRAILKILL.
